UNITED STATES PATENT OFFICE.

SAMUEL FLEISCHMANN, OF INDIANAPOLIS, INDIANA. ASSIGNOR OF ONE-HALF TO
JOSEPH BRAUN, OF INDIANAPOLIS, INDIANA.

FENDER FOR VEHICLES.

1,072,108.

Specification of Letters Patent. Patented Sept. 2, 1913.

Application filed May 22, 1911. Serial No. 628,790.

To all whom it may concern:

Be it known that I, SAMUEL FLEISCHMANN, a citizen of the German Empire, and a resident of Indianapolis, county of Marion, and State of Indiana, have invented a certain useful Fender for Vehicles; and I do hereby declare that the following is a full, clear, and exact description thereof, reference being had to the accompanying drawings.

The object of this invention is to provide an improved construction of fenders for vehicles, such as automobiles, street cars and like vehicles, but the invention has been made with particular reference for use with automobiles.

The nature of the invention will be understood from the accompanying drawings and the following description and claims.

In the drawings, Figure 1 is a front elevation of an automobile equipped with the fender. Fig. 2 is a perspective view of the fender along with the upper portion of the left-hand wheel guard broken away so as not to obscure other parts of the device in the drawing. Fig. 3 is a plan view of one side portion of the fender, and on a larger scale, parts being broken away. Fig. 4 is a side elevation of the fender when in normal condition. Fig. 5 is the same as Fig. 4, with the parts in their operative position after collision or operation by the chauffeur. Fig. 6 is a central, vertical section through what appears in Fig. 4, the front rail or bar and caster wheel being omitted. Fig. 7 is a section on the line 7-7 of Fig. 6, with parts cut away to show details of construction. Fig. 8 is a rear elevation of the portion of the device associated with the bell or signal apparatus, parts being broken away. Fig. 9 is a plan view of the same, parts being broken away and parts shown by dotted lines in altered position. Fig. 10 is a plan view on a larger scale of the means for supporting the wheel guard. Fig. 11 is a rear view of the right-hand end portion of Fig. 10. In Fig. 12 the left-hand portion is an elevation of the wheel guard and the right-hand portion is a section on the line 12-12 of Fig. 10. Figs. 13, 14 and 15 are details of the means whereby the chauffeur operates and controls the fender.

In detail there is shown herein an automobile 20 having front wheels 21 and an axle 22 of familiar type, but so far as this

invention is concerned, the particular construction of the vehicle is immaterial as it may be used with any type of vehicle.

The fender is formed essentially of a front arm or tube 23, a rear bar 24, side members 25 and intermediate bars 26 which extend longitudinally of the vehicle and are connected at each end with the front and rear bars 23 and 24. The side members of the fender are formed as shown in Figs. 3 to 6. Each consists of a horizontal rear part 125 and a forward portion 25 which portions are hinged together at 28 about midway of the length of the fender. These tubes are hinged on the underside so that the forward portion of the fender can drop down at an inclination, as shown in Fig. 5. Within the forward tube 25 a push bar or rod 30 is located extending from a point near the juncture of the tubes 25 and 125 and protruding beyond the outer end of the tube 25, as shown in Fig. 4, where it is pivotally mounted on the front bar 23 of the fender. Near each end the front bar 23 is surrounded by a clamping sleeve 31 which has a pair of horizontally disposed ears 32 between which the flattened outer end of the rod 30 is located and through which a bolt 33 extends. This gives the parts 23 and 30 a slight freedom horizontally relative to each other. The outer end of the tube 25 is reduced by a sleeve 34 fixedly secured in it and likewise the inner end has a fixed sleeve 35 and a collar 36 is secured around the rod 30 by a pin 37 within the tube 25 and adjacent the inner surface of the sleeve 34. A spiral spring 38 lies within the tube 25 between the sleeve 35 and collar 36 so as to tend to force the rod 30 outwardly, but this movement is limited by the collar 36 and the sleeve 34. When the front bar 23 strikes any object, it can yield because of the spring mounting of the rod 30 as it can have inward movement as far as the spring 38 will permit. The tube 125, forming part of the side member of the fender, also has a rod 40 in it corresponding with and abutting against the rod 30 so that as the rod 30 is pushed inwardly, a corresponding movement is given to the rod 40, although its movement is limited by a pin 41 projecting from it in a slot 42 in a tube 125, as shown by dotted lines in Fig. 6.

The fender is supported from the axle of the automobile as follows: The vertical sup-

ports each consist of a tube 50, see Fig. 6, which near its upper end is secured to one half 51 of a clamping tube which surrounds and grasps the axle 22. The other member 52 of the clamp is hinged to the stationary member 51 at the point 53 to the front end of the member 52 and the lower end of said members are clamped by a bolt 54. The inner surfaces of these clamping members 51 and 52 are toothed to enable them to more effectually clutch the axle 22. To assist in this a set screw 55 is provided which extends through the member 52 of the clamp and presses against the axle. This clamp 15 maintains the supporting tube 50 in a vertical position. Said tube has within it fixed sleeves 56 and 57, one near the upper end and one near the lower end and within them a rod 58 is located and held, but so as to have vertical movement independently of the tube 50. Downward movement of the rod 58 is limited by a pin 59 above the upper sleeve 56. Also the downward movement of the rod 58 is resisted by a spiral 20 spring 60 which surrounds the rod 58 and lies between the lower sleeve 57 and a washer 61 surrounding the rod 58 and lying against a pin 62 extending through said rod. The lower end of the rod 58 is secured rigidly 25 in an arm portion 63 extending upwardly from the horizontal tube 125 of the end member of the fender, see Fig. 6, and said part 63 is surrounded by the tube 50 of the supporting portion of the device, see Fig. 7. 30 This arrangement furnishes a yielding support for the fender, the vertical movement of the fender being controlled by the spring 60. It also permits some horizontal oscillatory movement of the fender relative to 35 the tubes 50 of the supporting portions of the device, while the automobile is turning a corner for instance, but said supporting means tends to hold the fender normally in a straight forward position. This is done 40 by the forwardly extending A-shaped teeth 65 on the tube 125 adjacent the front and rear surfaces of the extending portion 63, see Figs. 6 and 7, which project into corresponding notches in the lower end of the 45 tube 50. These notches and projections tend to hold the fender straight and permit lateral movement of the fender and when such lateral movement occurs, the teeth 65 and the tube 125 and rod 58 are thrown downwardly enough to permit lateral oscillation 50 of the fender. The spring 60 tends to hold the fender up and to hold the teeth 65 in their notches. 55 When the rods 30 and 40 are in their normal position, as shown in Fig. 6, the forward end of the rod 40 projects far enough into the sleeve 35 to support the forward part of the fender in a horizontal position, as seen in Fig. 6, but when the rods 30 and 60 40 are pushed rearwardly, part of the fender drops downwardly into the position shown in Fig. 5. The springs 70 tend to support the forward portion of the fender in the normal horizontal position. These springs are formed spirally at their rear ends where 70 they are secured by bolts 71 between ears 72 which extend up from a sleeve 73 secured on the tube 125. The forward ends of the springs 70 project loosely under a roller 76 between ears 77 on a ring 78 which surrounds the forward portion of the tube 25 forming the end member of the fender. Hence, the forward end of the spring 70 has longitudinal play under the roller 76, as shown by comparison of Figs. 4 and 5. 75 When the forward portion of the fender drops down, it is supported by rollers or casters 80 mounted in frames 81 secured by the clamps 82 to the front tube 23 near its ends. The forward portion of the fender is also held in its normal horizontal position by hook arms 86, there being one on each side of each end member of the fender and said arms are fulcrumed on bolts 85 extending from the tube 25 and above and to one side of the fulcrum 28. The arms project rearwardly and have a hook on the rear end of each adapted to catch on a pin 87 extending laterally from the rear tube 125, see Fig. 4. The arms are pressed downwardly into engaging position by the springs 88 which are mounted at one end on the bolts 85 and at the other end bear down on the lugs 89 on the rear portions of the arms 84. Each arm is provided near its rear end 90 with a downwardly extending cam projection 90 and in front of said cam projection the pin 41 projects from the rod 40 through the slot 42 in the tube 125. Hence normally the four arms 84 by catching over the pins 87 will support the forward end of the fender in its upper position, but as soon as there is a collision with the forward end of the fender, the rods 40 are moved rearwardly and such movement of the rods will 100 cause corresponding movement of the pins 41 and they will disengage the catch arms 84 from the pins 87 and then the forward end of the fender will drop by gravity. The springs 70, it must be understood, are not 105 strong enough in themselves to support the forward end of the fender; they merely assist. 110 The rear bar 24 of the fender is supported somewhat by the springs 92 suspended from a rectangular bar 93 which at its ends is supported from the brackets 94 clamped on the supporting tubes 50, as shown in Figs. 2, 4 and 15. 115 Means are provided for enabling the chauffeur to throw down the forward end of the fender, when it is desired. This consists of a push rod 95 which projects from the underside of the car and has a pedal 96 on the end of it against which the chauffeur 120 125

can place his foot and when he pushes forwardly, he gives a forward movement to the upper end of the double rock lever 97 which is fulcrumed between its ends at 98 on a bar 99 rigidly secured to the bar 93 and that causes the lower ends of the rock lever 97 to move rearwardly and push rearwardly the bar 100. This bar 100 is bifurcated at its ends and secured to the reduced extension 101 from the castings 102 which are secured to the rear ends of each rod 40. A bolt 103 secures the parts 100 and 101 together, as shown in Fig. 6. Therefore, when the pedal 96 is pushed, as has been explained, the rods 40 will be drawn rearwardly and the rearward movement of the pins 41 will disengage the catches 86 on the arms 84 and permit the forward end of the fender to drop down. This is done by the chauffeur as quickly as he sees danger of collision with a person.

In connection with the foregoing, there is a signal apparatus actuated by the casting 102 on the rear ends of the rods 40, see Fig. 6. A plate 104 is secured on the rearward extension 105 from the tube 125 and has a post 106 supporting a gong 107. On said plate 104 a hammer 108 is fulcrumed at 109 and actuated by a spring 110 which is secured at one end to the hammer and at the other end to a catch 111 on the plate 104, see Fig. 9. The hammer is withdrawn by the trip 112 pivoted at 113 on a plate 114 which is fulcrumed at one end at 115 on the plate 104. The plate 115 near one end has a slot 116 through which a bolt 117 extends from the casting 102 on the end of the rod 40. Therefore, the rearward movement of the rod 40 will move said parts from the full line position to the dotted line position, see Fig. 9, and cause the trip 112 to engage a lug 118 on the underside of the hammer and throw the hammer. The spring 120 extends from the trip 112 to a point 121 on the plate 104 to return the parts to their normal positions. A stop 122 limits the movement of the hammer and a stop 123 limits the movement of the plate 114. However, the particular construction of this gong is immaterial, so long as it is arranged in such a manner that the rearward movement of the rods 40 will actuate it and give a signal.

The wheel guards 130 are skeleton metal frames adapted to loosely surround a portion or segment of each of the front wheels, but not to bind the same so as to interfere with the operation of the wheels. These are indicated in Figs. 1 and 2, and more in detail in Fig. 12. Rollers 131 are located in each side of the guards 130 adapted to engage the sides of the tires of the wheels and prevent the tires from coming in contact with the remainder of the guard. Each guard is secured at its lower end to a semi-

circular metal frame piece 132 which is pivoted at 133 to an arm 134 which extends rearwardly from the end of the rod 234 at each of the front tubes 23. The tube 23, as shown in Fig. 12, has in it two sleeves 135 and 136 through which the rod 234 extends. Said rod has a rectangular portion where it passes through the sleeve 135 and a cylindrical portion where it passes through the sleeve 136 and since the sleeve 135 is rigidly secured to the sleeve 23, said sleeve tends to hold the arm 134 in a horizontal position. It, however, is assisted in this function by the arm 137 which is secured on the outside of the sleeve 23 near its end and projects rearwardly and carries a pin 138 which lies under the rear end of the arm 134 and tends to support it. The semi-circular frame 132 is yieldingly mounted on the arm 134 and is yieldingly guided by the spring 140 coiled about the pin 141 in the arm 134 and with its ends bearing upon said frame 132. The two ends extend in opposite directions, one bearing against the forward side of the wheel guard and the other end bearing against the rearward portion thereof so that the two ends of said spring counteract each other in yieldingly holding the wheel guard in place. Two fingers 142 project from the guard above the springs 140 to coöperate with it in holding the guard in place. The sleeve 136 is reciprocable in the arm 23. Likewise the forward end of each rod 234 has movement in and out of the front tube 23, as shown in Fig. 12, it being held in its inward position by a spiral spring 143 to one side of the sleeve 136 and connected with the inner end of said rod 234 by means not shown. This permits the arms 134 which carry the shield to have lateral movement as the wheels of the automobile are turned, and the entire fender is shifted by the wheels to some extent from side to side as the wheels turn, inasmuch as the members of the fender are pivoted together so as to permit such lateral oscillating movement. Thus, in turning a corner the wheels will be turned first and they will, through their engagement with the wheel guards, move the forward end of the fender in the same direction so that said fender will tend to turn before the automobile body turns. This is an important feature of the invention, as by it the fender can be used in connection with automobiles and the wheels thereof, so as to turn in advance of the automobile body.

I claim as my invention:

1. The combination with a vehicle and the forward wheels thereof, of a fender suspended in front of the vehicle, and means adapted to be engaged by the wheels so that the fender will be turned by the wheels in advance of the vehicle, substantially as set forth.

2. The combination with a vehicle having front wheels, of a fender having a receiving frame mounted in connection with the forward portion of said vehicle, wheel guards carried by the receiving frame in position to envelop the tire of the forward portion of the wheels, and means for mounting said wheel guards in connection with the main part of the receiving frame so that the wheel guards may have some lateral play or movement independently of the receiving frame. 5
3. The combination with a vehicle and wheels adapted to be turned independently of the vehicle body for transporting the same, of a fender mounted in connection with the forward portion of the vehicle and consisting of parts pivoted together so that the forward portion of the fender is laterally movable, guards for the front portions of the front wheels, and means for mounting said guards in connection with the front portion of the fender so that they will have some movement independently of the front portion of the fender and will also move in connection with the front portion of the fender as the wheels are turned. 10
4. A fender for vehicles including a rear portion mounted in a horizontal position and a forward portion hinged to said rear portion about midway of the fender so that the forward portion of the fender may be dropped down to the ground, catches on one portion engaging projections on the other portion for maintaining the forward portion of the fender in its horizontal position, and means actuated by the rearward movement of a part of the fender for automatically disengaging said catches. 15
5. A fender for vehicles including a rear portion mounted in a horizontal position and a forward portion hinged to said rear portion about midway of the fender so that the forward portion of the fender may be dropped down to the ground, catches on one portion engaging projections on the other portion for maintaining the forward portion of the fender in its horizontal position, means actuated by the rearward movement of a part of the fender for automatically disengaging said catches and springs secured in connection with said rear portion and engaging the forward part of the forward portion to assist in supporting the same in its horizontal position. 20
6. A fender for vehicles including a rear portion mounted in a horizontal position and a forward portion combined with said rear portion about midway of the fender so that the forward portion of the fender may be dropped down to the ground, catches on one portion engaging projections on the other portion for maintaining the forward portion of the fender in its horizontal position, means actuated by the rearward movement of a part of the fender for automatically disengaging said catches and permitting the forward end of said fender to drop down. 25
7. A vehicle fender including a fender frame having at each side a pair of rods in alignment with each other and with their ends abutting supporting means at each side of the fender in which said rods are mounted so as to be movable longitudinally thereof, said means being hinged at a point near the adjacent ends of said rods, catches mounted in connection with said supporting means and engaging a projection on one of each pair of rods for locking the same so as to hold the forward part of the frame in its elevated position, and means moved by the rearward movement of said rods for disengaging said catches. 30
8. A fender for vehicles including a rear portion mounted in a horizontal position and a forward portion combined with said rear portion about midway of the fender so that the forward portion of the fender may be dropped down to the ground, catches on the forward portion adapted to engage projections on the rear portion for maintaining the forward portion of the fender in its horizontal position, means actuated by the rearward movement of a part of the fender for automatically disengaging said catches, and means extending rearwardly from said fender, whereby the same may be operated by a person in the vehicle to lower the forward portion of the fender. 35
9. A fender for vehicles including a rear portion mounted in a horizontal position and a forward portion combined with said rear portion about midway of the fender so that the forward portion of the fender may be dropped down to the ground, catches on the forward portion engaging the rear portion for maintaining the forward portion of the fender in its horizontal position, means actuated by the rearward movement of a part of the fender for automatically disengaging said catches, a frame supported by said forward and rear portions, a push bar adapted to project into the vehicle where it can be operated, a rocking lever the upper end of which may be pushed forwardly by the said push bar, and means engaged by the lower end of said rocking lever for moving said fender frame rearwardly for disengaging said catches and permitting the forward end of said fender to drop down. 40
10. A vehicle fender including a vertical member at each side adapted to be rigidly secured to the vehicle, a rod yieldingly mounted therein, a horizontal forwardly extending tubular member secured to the lower end thereof, a bar connecting the rear ends of said tubular members, a tube hinged to the front end of each of said horizontal tubular members, whereby the forward end 45

may be dropped to the ground, a rod in each of said horizontal tubular members adapted to extend into said hinged tubes, a rod in each of said hinged tubes abutting said horizontal tube rods, a bar connecting the front ends thereof, bars connecting said front connecting bar and said bar connecting the rear ends of said horizontal tubular members, latches on said hinged tubes engaging said horizontal tubes and adapted to hold the hinged tubes horizontal, and means on said horizontal tube rods for automatically disengaging said catches when pressed toward the rear by said rods in said hinged tubes for allowing the front end of the fender to drop down.

11. A vehicle fender including a vertical member at each side adapted to be rigidly secured to the vehicle, a rod yieldingly mounted therein, a horizontal forwardly extending tubular member secured to the lower end thereof, a bar connecting the rear ends of said tubular members, a tube hinged to the front end of each of said horizontal tubular members, whereby the forward end

may be dropped to the ground, a rod in each of said horizontal tubular members adapted to extend into said hinged tubes, a rod in each of said hinged tubes abutting said horizontal tube rods, a bar connecting the front ends thereof, bars connecting said front connecting bar and said bar connecting the rear ends of said horizontal tubular members, latches on said hinged tubes engaging said horizontal tubes and adapted to hold the hinged tubes horizontal, means on said horizontal tube rods for automatically disengaging said catches when pressed toward the rear by said rods in said hinged tubes, and independent means operated from within the vehicle for disengaging said catches for allowing the front end of the fender to drop down.

In witness whereof, I have hereunto affixed my signature in the presence of the witnesses herein named.

SAMUEL FLEISCHMANN.
